W. STRITTMATTER.

MEANS FOR MARKING WOUND STRIP MATERIAL.

APPLICATION FILED FEB. 19, 1921.

1,387,330.

Patented Aug. 9, 1921.

WITNESS

Mr. Mell.

INVENTOR,
William Strittmatter,
John Strittmatter,
ATTORNEY

UNITED STATES PATENT OFFICE.

WILLIAM STRITTMATTER, OF NORTH BERGEN, NEW JERSEY.

MEANS FOR MARKING WOUND STRIP MATERIAL.

1,387,330.

Specification of Letters Patent.

Patented Aug. 9, 1921.

Application filed February 19, 1921. Serial No. 446,496.

To all whom it may concern:

Be it known that I, WILLIAM STRITTMATTER, a citizen of the United States, residing at town of North Bergen, in the county of Hudson and State of New Jersey, have invented certain new and useful Improvements in Means for Marking Wound Strip Material, of which the following is a specification.

10 The object of this invention is to provide means whereby the yardage may be indicated by marking in some way, as by printing, on a strip as it is wound up on a suitable core, the same being so constructed as 15 to be simple in form, reliable in operation and adapted to permit the core, when a fully wound package of the strip material has been formed, to be removed from the means for rotating it and a fresh one applied. Such 20 a means as my invention contemplates is of great value in blocking ribbon and the like, where usually paper is wound up with the ribbon and both the manufacturer and the dealer require to know the number of 25 yards that a package contains. When my apparatus is used for such a purpose the paper strip affords the element whereon the marking is done.

In the drawing, illustrating one embodiment of my invention by way of example,

30 Figure 1 is a rear elevation; and

Fig. 2 a sectional view on line 2—2, Fig. 1.

On a base *a*, which may be the top of a table or bench, is arranged a support *b* affording bearings for the rotary shaft *c* of a face-plate *d*, the shaft being equipped with a pulley *e* adapted to be driven by a belt (not shown); the support also carries, aligned with the shaft and adjustable toward and 40 from the same by means of the screw *f*, a spindle *g* on which is journaled the face-plate *h*. *i* is the block adapted to be gripped between the face-plates and to be rotated from face-plate *d* when shaft *c* is driven; 45 on this block as a core the material to be wound up, including a ribbon or the like *A* and a paper strip *B*, is wound. The foregoing constitute the usual elements of a ribbon blocking apparatus.

50 Support *b* includes a post *j* having a

bracket *k* in which is pivoted an arm *l* and also having a bracket *m* in which is journaled a pulley *n* over which extends a flexible connection *o* which extends from the arm *l* down through a hole in the base *a* 55 to a treadle *p* adapted to be depressed by the foot of the attendant, the arm being normally urged toward the axis of rotation of the block *i* by the weight of itself and the parts it carries.

In arm *l* is journaled a friction-wheel or "sand-wheel", *p'*, the same having a sanded or otherwise roughened or gripping periphery which when it bears on the material being wound on the rotated block causes said 65 wheel to rotate in its bearings. On an arbor *q* journaled in the wheel near its periphery and parallel with its axis of rotation are fixed a ratchet-wheel *r*, the same being at one side of the wheel, and a marker *s*, the latter being in the present case a wheel with 70 serial type, as 1, 2, 3, etc., arranged on and around its periphery, which protrudes through a slot *t* formed in the periphery or rim of the wheel *p'*. The marker is held to 75 any position to which it may be turned, *i. e.*, with one of its indices in the radial line of wheel *p'* which coincides with the axis of rotation of the marker and facing outwardly, by a spring pawl *u* attached to 80 wheel *p'* and engaging the toothed periphery of the ratchet wheel.

The marker being in the present instance a printing device means is provided for inking its type automatically, for which purpose *v* is an inking roller mounted in a bracket *w* attached to the arm *l* in position to be wiped by that one of the type, as it is carried past the roller, which happens then to face peripherally outward of 85 90 wheel *p'*.

For causing step-by-step rotation of the marker, so that its type will be successively presented to the material being wound, I provide a fixed pawl or lug *x* which may be 95 attached to arm *l* so as to be in the path of that portion of the toothed periphery of the ratchet wheel *r* which happens to be outward with reference to wheel *p'* when the ratchet wheel passes said lug and so, by en- 100

gaging a tooth of the ratchet wheel, turn the latter and the marker a partial revolution.

In using the apparatus the parts occupy the position shown in the drawings when the material is being blocked, the wheel p' then resting with its periphery against the material, its sanded periphery engaging the ribbon and the plane of rotation of the marker with the wheel p' being opposite one edge portion of the paper strip, which is, as usual, exposed by the ribbon. On every revolution of the wheel p' that one of the type or indices of the marker which protrudes through slot t bears on the paper strip and leaves an imprint thereon and thereupon the marker is turned a partial revolution in the wheel p' so as to bring the next type or index into protruding relation at the slot for the next revolution, this latter type or index then receiving ink from the roller v . The markings produced in or on the material being wound will be spaced equal distances apart, the intervals being equivalent in length to the circumference of the wheel p' . When a complete wound package has been formed the attendant, by depressing treadle p , withdraws the marking mechanism clear of the package, arm l swinging back on its pivot, removes the filled block and inserts between the face-plates an empty one; then, having started the winding up of another package, the treadle is released and the marking mechanism returned to its normal position.

As the wheel p' by its tendency to retard the ribbon might in the case of wide ribbon of a flimsy texture cause backward displacement of one edge of the ribbon relatively to the other I may in such cases apply to the spindle y , which affords an axial support for the wheel p' , a supplemental friction wheel z .

So far as I am aware it is new in the art of marking on a roll of strip material as the roll is being formed, and therefore the mass thereof gradually increases in diameter, to provide mechanism for marking the material at predetermined intervals lengthwise thereof which is normally urged toward but is movable away from the axis of the mass and includes a rotary prime mover (as wheel p') arranged to bear peripherally thereof on the periphery of said mass and be rotated by the rotating already-wound mass of material. Since the marking is in accordance with the ultimate object to be such as to indicate at intervals on the material the number of yards wound up the marking mechanism in the best form also includes a marker having serial indices and movable in the prime mover to present its indices one after another outwardly at the periphery of said prime mover, as by being a rotary member, as s , on the periph-

ery of which the serial indices are arranged; and means is further provided in the best form for also moving the marker automatically at intervals as $r-x$, so as to present its indices progressively to the material.

Having thus fully described my invention, what I claim and desire to secure by Letters Patent is:

1. In combination, means to wind up strip material on a definite axis and mechanism, normally urged toward but movable away from said axis, for marking the material at predetermined intervals lengthwise thereof including a rotary prime mover arranged to bear peripherally thereof on the periphery of and be rotated by the rotating already-wound mass of material.

2. In combination, means to wind up strip material on a definite axis and mechanism, normally urged toward but movable away from said axis, for marking the material at predetermined intervals lengthwise thereof including a rotary prime mover arranged to bear peripherally thereof on the periphery of and be rotated by the rotating already-wound mass of material and a marker having serial marking indices and movable in the prime mover to present said indices one after another outwardly at the periphery of the prime mover and in position to engage said mass.

3. In combination, means to wind up strip material on a definite axis and mechanism, normally urged toward but movable away from said axis, for marking the material at predetermined intervals lengthwise thereof including a rotary prime mover arranged to bear peripherally thereof on the periphery of and be rotated by the rotating already-wound mass of material, a marker having serial marking indices and movable in the prime mover to present said indices one after another outwardly at the periphery of the prime mover and in position to engage said mass, and means to move the marker step by step, once for each revolution of the prime mover.

4. In combination, means to wind up strip material on a definite axis and mechanism, normally urged toward but movable away from said axis, for marking the material at predetermined intervals lengthwise thereof including a rotary prime mover arranged to bear peripherally thereof on the periphery of and be rotated by the rotating already-wound mass of material and a rotary marker arranged to engage at its periphery on the periphery of said mass and journaled in the prime mover and having serial marking indices arranged on and around its periphery.

5. In combination, means to wind up strip material on a definite axis and mechanism, normally urged toward but movable

away from said axis, for marking the material at predetermined intervals lengthwise thereof including a marker having serial marking indices and movable in said mechanism to present said indices one after another to the already-wound mass of material peripherally thereof, and a prime mover arranged to bear peripherally there-

of on the periphery of and be rotated by the rotating already-wound mass of material and adapted to move the marker at each revolution of said prime mover into marking engagement with said mass. 10

In testimony whereof I affix my signature.

WILLIAM STRITTMATTER.
